COMBINATION OUTER DOORS FOR DWELLINGS

Ora A. Hinton, Long Island City, N. Y., and Louise De Stramp, Washington, D. C.

Application May 29, 1942, Serial No. 445,062

4 Claims. (Cl. 160—95)

This invention relates to outer doors for dwellings or homes, and more particularly to a construction involving duplex or double doors, both supported to swing on a single or common pivotal center.

Objects of constructions are found in means, devices or attachments for maintaining a main or house door and an attached screen or other companion door in an open position, as a unit, means being also provided for maintaining the screen or other door in a closed position and the usual or house door in an open position; and a third position would be shown as with both doors in a closed or locked position.

Inventive features of construction are present in the parts and attachments carried by the frame of the screen door, permitting face to face attachment in the normal employment of both doors as a unit.

Other objects of the invention are to effect simplicity and efficiency in such constructions and to provide an extremely simple construction which is economical and reliable in operation, and not costly to build.

Still other objects of the invention will appear as the description proceeds and while herein details of the invention are described in the specification and some of the claims, the invention as described in the broader claims is not limited to these, and many and various changes may be made without departing from the scope of the invention as claimed in the broader claims.

Normally, the opposed faces of the doors are never brought into actual contact, but are maintained in a slightly separated position by suitable means, such as rubber buttons mounted on short screw shanks which are driven into the material of one or the other of said doors, and this method avoids undue noise when the doors are brought into face contact, the said rubber buttons maintaining a bare $\frac{1}{8}$ inch space between the doors.

We also provide a safety device for guarding against the locking of the screen door, only when the house door is open or swung inwardly on its hinges, and further for unlocking the screen door should the house door be blown shut by a sudden draft.

Other novel elements comprising parts of this structure will hereinafter be pointed out in the following description and then pointed out in the appended claims.

In the drawings forming part of this specification—

Figure 1 illustrates a fragmentary outer face view of a screen door showing its hinged con-

nnection with a portion of the usual house door, and showing means for operating a latch-bolt automatically;

Figure 2 illustrates a horizontal section taken about on the line 2—2 of Fig. 1, parts being in dotted lines;

Figure 3 illustrates a view similar to Fig. 2, but showing a lock bolt drawn back into an inoperative position by the closing of one of said doors;

Figure 4 illustrates a horizontal section through a top or bottom hinge constructed according to this invention, the doors being shown in open dot and dash positions;

Figures 5, 6 and 7 show diagrammatically operative positions the combination parts of the outer door may assume;

Figure 8 illustrates a detail front view of a channel plate employed where the key-hole and latch-handle appear when the double doors are closed and locked together and with parts omitted;

Figure 9 illustrates a detail section of the lower portions of the interlocked doors, showing mail delivery slots covered by a spring pressed plate on the outer face of the screen door and a gravity drop plate on the inner face of the house door and a separating button between said doors;

Figure 10 illustrates similar doors spaced as shown and connected by a spring actuated catch-hook for maintaining the doors against separation;

Figure 11 illustrates a detail horizontal section disclosing the safety device above referred to;

Figure 12 illustrates a fragmentary elevation of an inner slide plate;

Figure 13 illustrates a similar face elevation of a companion slide plate operable with the slide plate of Fig. 12, for opening the windows for the key-hole and handle of the house door to register therewith;

Figure 14 illustrates a detail cross section of a part of the screen door supporting hinge, taken on the dot and dash line 14—14 of Fig. 1; and

Figure 15 illustrates a detailed view of the upper end of the hinge pintle.

We will now proceed to describe our invention in detail by employing reference numerals in all of the several figures as follows:

Referring now to the drawings, the numeral 10 designates the doorway or outer entrance to a dwelling or like structure, said doorway having a suitable frame 11, provided with convenient bolt or latch sockets 12, for receiving locking and safety devices to be hereinafter described.

Referring more particularly to Figs. 1, 2 and 3 of the drawings, the main or house door 13 is supported on three separate hinges (not all shown). One of the said hinges 14 is shown in Figs. 1, 2 and 3 as applied to near the central or lock-rail portion of the door 13, while upper and lower hinges 15 (Fig. 4) may be employed to connect the top and bottom portions of the stiles 16 of the door 13 to its frame.

The screen or other door 17 comprising a ventilating companion for a non-ventilating house door comprises many inventive features not heretofore known to the public, and its construction and operation will now be carefully disclosed to those familiar with this art. The screen or other door 17, positioned as the outer door of the combination, is carried on the extended upper ends 18 of the usual pintles or pivot pins 19 of the said hinges 14, and for preventing the pins 19 from turning in the alined eyes or loops of the main hinge members, we preferably employ set screws 20 for clamping said pins 19 against rotation, as will be understood (see Figure 1 of the drawings).

In the practice of our invention, it is desirable to impart a closing urge to the outer screen door when said doors are not connected, one to the other, by a spring-actuated interlocking hook or the like, shown at 21, in Fig. 10 of the drawings, when both doors are swung together to an open position, as in Fig. 5, for entirely freeing the doorway.

The interlocking hook 21 preferably swings downward as shown in dotted lines in the said Fig. 10, when a push button 22 is pressed, to cause a nose 23, to rock the hook 21, as described, and cause said hook to clear a catch-plate 24, thus disconnecting the combination doors 13 and 17, as will be understood, to permit them to swing independently.

The outer or screen door 17 is preferably mortised at and near the point of connection of its lock-rail 25, with the stiles 26, as indicated in a general manner by the numeral 27.

An elongated channeled face plate 28 is made fast to the outer face of the swinging or free stile 26 of the screen door 17, by screws or pins 29, and said face plate 28, in its indented face portion, is provided with an upper window 30, registering with a key-hole plate 31 (see Fig. 8), through which a key may be passed for unlocking the inner or house door, and a lower window 32, may be formed in the said face plate 28, through which a house door handle 33 and latch lever 34 may project for convenient operation from the porch or sidewalk of the dwelling, as will be understood.

Referring to Fig. 9 of the drawings, one of many spacing buttons 35 is employed between the doors 13 and 17 to prevent face to face contact thereof, and near the lower ends of these doors are provided coincident mail slots 36 in the house door and at 37 in the screen door, the former having a closing gravity plate 38, while the latter is provided with a spring-actuated plate 39 for closing the mail slot from the outside.

The normal or closed position of the interlocked inner and outer correlated doors 13 and 17 is best disclosed in Figure 3 of the drawings, and it is in this position that the inner or house door is locked and the screen door is confined between a vertical bead or shoulder 40 and the spacing buttons 35.

Slidable shutters 41 and 42 are employed to close the windows 30 and 32 when the house door

is swung into the room of the dwelling and the screen door is in its locked position, barring entrance to said room. The shutter 41 (Fig. 12), is formed with a lateral arm 43, having a trip-slot 54 to receive a trip pin 45, extending inwardly from a slide bar 46 formed with an upwardly directed push handle 47 screwed to the rear end of a slide bolt 48 for normally locking the screen door 17.

The lock bolt 48 may also be pulled back out of operation against the action of springs contained in suitable bores in the rear end of the lock bolt by grasping a thumb piece 49 in Figs. 2 and 3, and in Fig. 12 of the drawings the inner lateral arm 43 of the window closing shutters is shown with a follower slot 50, through which a pin or roller 51 travels when the house door 13 swings on its pivot and this roller 51 is carried by the outer lateral arm 52 of the outer window closing shutter 42 (Fig. 13) and this lateral arm 52 is formed with a slot 53 similar to the slot 44 of the opposite shutter 41 (see Fig. 1).

By referring to Figure 11, we have devised a safety lock for combination doors for preventing inadvertence or carelessness in opening and closing the doors, and for this purpose we employ a short revoluble gear shank 53' with a handle 54 so that when the house door 13 is unlocked and swung open, the gear shank is rotated about half a revolution by an operator, thus sliding a bolt 55 to the right and into its socket 56 for locking the screen door and for projecting an upper bolt 57 outwardly for presenting its beveled face 58 in the path of the house door 13, should it be closed by a draft of air, and thus the house door snap-bolt will automatically re-lock itself for safety, and the screen door bolt will again be withdrawn from a locked position, as will be understood.

Referring to Fig. 15 of the drawings, the upper end of each pintle 18 is formed with a kerf or cross-cut 59, into which is turned the upper terminals 60 of torsion springs 61 terminating at their lower ends in torsion exerting arms 62, for urging, through hinge plates 63, the screen or outer door 17 constantly to a closed position against the stops or shoulders 40, best shown in Figs. 2 and 3 of the drawings.

The spring terminals 60 are set or locked in the bottoms of the kerfs 59 by clamp screws 64, which enter through central holes through the tops of said thimbles 65, as shown in Fig. 15 of the drawings and by the above construction, the screen or other door 17 may swing independently of the house door 13, when said doors are not interconnected, as will be understood.

The door hinges 14, 15 at the lock-rail and at the top and bottom of the companion doors 13 and 17 are somewhat similar except that the attaching plate 66 for the screen door at the lock rail 25 is provided with inside grooves 67, for receiving a pull-chain 68, controlling the stretch of parallel springs 69, for at all times holding the chain 68 taut around the swinging outer corner 70 of the house door, as clearly shown in Figs. 2 and 3 of the drawings, and this position of the parts acts to urge the house door 13 around and inward on its pivot. When closing the house door the chain which is in engagement with the inner corner of the door is moved longitudinally and exerts a pull on the shutter mechanism and opens the shutter.

The door screen 71 of the door 17 may be attached to its wooden frame by retaining strips 72, as in Fig. 11, or in any other approved manner.

Guide bars 73 are riveted to a rear plate 74, and said plate is secured to the said lock rail of the screen door by screws or pins 75 best shown in Fig. 1, and these bars 73 serve to guide the lateral arms 43 and 52 of the window closing plates or gates 41 and 42.

The pull chain 68 operates through a metal tube 76 for the greater part of its length for guiding said chain and for assuring proper direction. As shown in Fig. 1, an auxiliary bolt 77 operable from 10 inside the house by a handle 78 may be employed.

We claim:

1. In combination, a house door for dwellings, a companion door mounted to operate through a single frame with said house door, said doors being connected as a unit, a knob on said house door, an open frame on said companion door adapted to receive the knob when said doors are joined as a unit, a shutter adapted to cover and uncover said open frame, and means adapted to 15 uncover said opening on the approach of said house door.

2. The combination of claim 1, in which the power for opening said shutter is derived from the closing movement of said house door.

3. In combination, a house door and a companion door mounted to operate through a single

frame, operating means actuated by the movement of the house door, an open frame on said companion door, a shutter adapted to cover and uncover said frame, and spring means urging said shutter to closed position on the opening movement of the house door, said operating means connected to said house door to open said shutter against said spring means on closing movement of said house door.

4. In combination, a house door and a companion door mounted to operate through a single frame, said doors being connected as a unit, operating means on said house door, an open frame on said companion door adapted to receive said operating means when the doors are joined as a unit, a shutter adapted to cover and uncover said frame, spring means urging said shutter to closed position on the opening movement of the house door, and means operatively connected to said house door to open said shutter against said spring means on closing movement of said house door whereby said operating means on said house door are received in said open frame of the companion door.
